UNITED STATES PATENT OFFICE.

HERBERT H. FREY, OF DETROIT, MICHIGAN

APPARATUS FOR COMPRESSING AIR.

1,001,132.

Specification of Letters Patent. Patented Aug. 22, 1911.

Application filed June 9, 1910. Serial No. 565,955.

To all whom it may concern:

Be it known that I, HERBERT H. FREY, a citizen of the United States, residing at Detroit, county of Wayne, State of Michigan, have invented a certain new and useful Improvement in Apparatus for Compressing Air, and declare the following to be a full, clear, and exact description of the same, such as will enable others skilled in the art to which it pertains to make and use the same, reference being had to the accompanying drawings, which form a part of this specification.

My invention relates to apparatus for compressing air and an object of my improvements is to provide an improved apparatus for compressing air and one which may be readily adapted to an internal combustion engine without necessitating changes in, or addition to, the engine. I secure this object in the device illustrated in the accompanying drawing, in which,—

Figure 1, is a sectional view of an apparatus embodying my invention, and so much of a gas engine as is necessary to illustrate its connection therewith. Fig. 2, is a view similar to Fig. 1, showing a modified form of apparatus embodying my invention.

A, indicates a part of a gas engine cylinder; B, is a pipe or conduit secured thereto, its bore communicating with the interior of said cylinder.

G, is a cylinder in which reciprocates a piston D; the pipe B communicates with the cylinder G at the center of its lower end.

C, is a projection extending upward from the center of the lower end of the cylinder G and having an aperture therethrough communicating with the bore of the pipe B.

E, is a stem extending upward from the center of the piston D.

J, is a cylinder coaxial, and communicating with the cylinder G and extending upward from the upper end of the cylinder G.

The diameter of the cylinder J is less than that of the cylinder G.

F, is a piston operated and adapted to reciprocate in the cylinder J. The stem E unites the pistons D and F.

K, is a projection extending downward from the center of the upward end of the cylinder J.

L, is a pipe through which compressed air is conducted to a reservoir or holder.

There is an aperture through the projection

K which opens to the interior of the cylinder J and to the bore of the pipe L.

M, is an inwardly opening automatic valve communicating with the atmosphere and with the interior of the cylinder J and located at the upper end of said cylinder.

N, are apertures through the wall of the cylinder J just above where the upper surface of the piston F comes at the lower end of the stroke of said piston.

H, is a hole extending inward from the lower surface of the piston D at the center thereof. The walls of the hole H are adapted to fit loosely over the projection C.

I, is a hole extending inward from the upper surface of the piston F and at the center thereof, the walls of said hole fit loosely over the projection K.

b, Fig. 1, is a nozzle communicating with the atmosphere and with the pipe B.

a, is an automatic valve adapted to open inward in the nozzle b.

The construction of the modified form shown in Fig. 2, is entirely similar to that of Fig. 1, except that in Fig. 1, the pistons D and F are united by an integral piece of smaller diameter and in Fig. 2, these pistons are united by an integral piece, or rod of larger diameter, and in Fig. 2, cup leathers P and Q are used in connection with the pistons F and D to secure a tight joint and in the former case to serve the purpose of the inlet valve M. In the device of Fig. 2, the lower end of the cylinder G is shown perforated and a flap valve a' is shown covering the perforations and adapted to automatically open inward, this construction being adapted to take the place of the nozzle and valve, b and a of Fig. 1.

The operation of the above described device is as follows:—When a vacuum is drawn in the cylinder A, in the operation of the engine, the pistons F and D are forced to the lower end of their travel. When compression takes place in the cylinder A, the pressure acts upon the lower end of the piston D to force it to the upper end of its stroke carrying the piston F with it and compressing the air in the upper end of the cylinder J and forcing the same out into the pipe L. As the area of the piston D is considerably greater than that of the piston F, a higher degree of pressure may be obtained in the cylinder J than is obtained in the gas engine cylinder A. The apertures

5 serve to admit air to form complete atmospheric pressure in the cylinder J at the lower end of the stroke of the piston F and also to permit of the exit of air from the cylinder G on the upstroke of the piston D.

In the form of the device shown in Fig. 1, the piston D is prevented from striking the lower end of the cylinder G, so as to make a noise by the air being imprisoned beneath the piston D to form a cushion, and gradually running out between the walls of the hole H and the outer walls of the projection C. The hole I and projection K act in the same way to prevent a violent contact of the piston F with the upper end of the cylinder J.

When a gas engine is running light or without doing work, it is usually throttled down so that it does not receive a full charge 20 and consequently the pressure on the return stroke is small. When the apparatus above described is attached to a gas engine cylinder the atmospheric air may enter through the valves a and a' to supply this deficiency 25 so that when this device is used with one cylinder of a multi-cylinder engine, the compression may be small in all of the other cylinders, except the one with which this apparatus is used and in one that it will 30 attain its normal value.

What I claim is:—

1. The combination of a gas engine cylinder A, a cylinder G communicating therewith by a conduit, B, a piston D adapted to 25 reciprocate in the cylinder G, a projection C

extending into the cylinder G and having an aperture therethrough communicating with the bore of said conduit, said piston being provided with a hole, the walls of which are adapted to fit loosely over said 40 projection, substantially as and for the purpose described.

2. The combination of a cylinder G, a passage forming a communication between said cylinder and a cylinder A in which compression is to take place; a piston in the cylinder G, a second cylinder J of less diameter than the cylinder G, a piston in the cylinder J, and means for connecting said pistons, a passage communicating with the outer air 50 located between the cylinder G and the compression apparatus, and a non-return valve opening inward in said passage.

3. The combination of a cylinder G, a passage forming a communication between said 55 cylinder and a cylinder A in which compression is to take place, a piston in the cylinder G, a second cylinder J of less diameter than the cylinder G, a piston in the cylinder J, and means for connecting said pistons, inlet and outlet passages to said cylinders and a non-return valve opening inward into the communication to the compression means.

In testimony whereof, I sign this specification in the presence of two witnesses.

HERBERT H. FREY.
